(57) **CLAIM**

The ornamental design for an analytical measuring instrument, as shown and described.

DESCRIPTION

FIG. 1 is a front perspective view of the analytical measuring instrument;

FIG. 2 is a top plan view of the FIG. 1 device;

FIG. 3 is a bottom plan view of the FIG. 1 device;

FIG. 4 is a left side elevation view of the FIG. 1 device;

FIG. 5 is a right side elevation view of the FIG. 1 device;

FIG. 6 is a rear elevation view of the FIG. 1 device; and,

FIG. 7 is a front elevation view of the FIG. 1 device.

The broken lines are for illustrating functional features and form no part of the claimed design.
